UNITED STATES PATENT OFFICE.

BEVERLY W. KEESE, OF ANTIGO, WISCONSIN, ASSIGNOR TO ANTIGO TRACTOR CORPORATION, OF ANTIGO, WISCONSIN, A CORPORATION OF WISCONSIN.

COMBINED GOVERNOR AND FAN MECHANISM FOR INTERNAL-COMBUSTION ENGINES.

Application filed August 7, 1922. Serial No. 580,380.

To all whom it may concern:

Be it known that I, BEVERLY W. KEESE, a citizen of the United States, and resident of Antigo, in the county of Langlade and 5 State of Wisconsin, have invented certain new and useful Improvements in Combined Governor and Fan Mechanism for Internal-Combustion Engines; and I do hereby declare that the following is a full, clear, and 10 exact description thereof.

This invention relates to combined fan and governor mechanism, and is particularly directed to a mechanism of this type suitable for use with internal combustion engines 15 such as those found upon tractors.

Objects of this invention are to provide a unitarily combined fan and governor for internal combustion engines; to provide such a device so constructed as to use the same 20 shaft, bearings, housing and similar parts; and to provide a substantially flexible drive for the fan and a positive drive for the governor.

Further objects are to provide a combined 25 fan and governor mechanism suitable for automotive apparatus, such as tractors, so organized that it may have both manual and automatic control; to provide a dust and oil proof housing for the parts; to provide means for readily adjusting the stress 30 imposed by resilient means associated with the governor and to provide a combined fan and governor of pleasing and attractive appearance.

35 An embodiment of the invention is shown in the accompanying drawing, in which

Figure 1 shows diagrammatically the relative positions of the combined governor and fan and other portions of the system.

40 Figure 2 is a vertical sectional view of the combined governor and fan.

Figure 3 is a horizontal sectional view of a portion of the structure shown in Figure 3.

45 Figure 4 is a transverse sectional view on the line 4-4 of Figure 3.

Figure 1 shows the general arrangement, and will first be described. In this figure, the engine casing, or a continuation thereof, is indicated at 1, to which is bolted the casing 2 for the unitary governor and fan mechanism. The drive shaft for this mechanism is indicated at 3, and projects forwardly thru the casing and carries the hub 4 of the fan, such fan conveniently being one 55 in which the projections 5 from the blades

are secured to the hub by means of a plurality of bolts 6. The casing 2 is equipped with a removable cap portion 7 so that the interior mechanism may be readily and conveniently reached. A control shaft 8 extends laterally outwardly thru this casing, and carries a crank arm 9 which is moved by the centrifugally responsive portions of the governor. The free end of this crank arm has pivotally mounted, thereon, a lever 10, whose lower end is connected by means of a rod 11 with the throttle valve crank arm 12, the outer casing 13 of such throttle valve being shown in Figure 1. The upper end of the lever 10 is connected by means of the rod 14 with the lower end 15 of a lever which is rigidly joined to the manually movable arm 16.

It will be seen from the structure thus far described that the action of the governor 75 may be readily modified by the manually controlled portions of the mechanism, and that the setting of the throttle valve may be controlled manually, while at the same time interposing the governor control.

The shaft 3 is equipped with a pinion 17 rigidly secured at its rear end adjacent the rear ball bearing 18. The pinion is directly connected by means of gearing with the engine shaft, so that the shaft 3 may be positively driven from the engine. The other end of the shaft has loosely secured thereto, the hub 4 of the fan, such hub being held against a shouldered portion 19 of the shaft by means of a nut 20 screwed upon the outer 80 end of such shaft. This hub is free to rotate with respect to the shaft, but is retained thereon against longitudinal movement. It has a threaded portion 21, upon which is screwed a disk 22, such disk accurately and 85 slidably fitting the machined surface 23 of the outer end of the casing 2. The rear portion of the hub 4 is carried by the ball bearings 24, as may be seen from Figure 2.

A governor bracket 24, which may be of 100 split formation, is secured to the shaft 3 by means of the clamping bolts 25. A helical spring 26 has one end rigidly secured in the governor bracket, and it has its other end rigidly secured in the hub 4. 105 It is spaced a slight distance from the shaft and its surrounding portions, so as to be free to yield under suddenly applied force. It will be seen, therefore, that although the shaft 3 is positively 110

driven from the internal combustion engine, that the fan and its connection with the shaft is not subjected to enormous stresses, due to sudden changes in the speed of rotation, but that such changes in the speed of rotation are modified by the spring 26 before they are transmitted to the fan. In this manner, it is possible to utilize a direct gear connection with the fan shaft without danger of imposing unsafe stresses upon the mechanism.

The governor bracket 24 is provided with a pair of overhanging rearwardly projecting arms 27, which are bifurcated, or 15 forked, with the legs 28 thereof, spaced a material distance apart. The weighted levers, which are the centrifugally responsive members, each comprise a rearwardly projecting weight 29, which has inwardly 20 projecting arms 30 pivotally joined to the legs 28 of the bracket by means of a pintle 31. One of these arms 30 has an inwardly offset portion constituting a rock arm 32, which may carry a roller 33 adjacent its 25 end. It is to be noted that the rollers 33 of the weighted levers are positioned upon opposite sides of the shaft 3, and bear against the forward end of a slidable sleeve 34 mounted upon such shaft. If desired, 30 this sleeve may be supplemented by a plurality of washers adjacent its ends, to further reduce friction. The pintles 31 are retained in position by suitable pins, and carry the coiled portion 35 of suitable 35 springs, whose terminal portions bear against the weighted portions of the levers and against the overhanging arms 27 of the governor bracket, as may be seen from Figures 2 and 3, thereby tending to force 40 the weighted portions 29 of the levers inwardly.

The transverse control shaft 8 carries, at its inner end within the casing, forked lever 36, provided with inwardly projecting pins 45 which may be equipped with rollers 37, if desired, and which bear against the rear end of the slidable sleeve 34. This shaft 8 is carried in a revolvably mounted bearing 38, which is locked in its adjusted position 50 by means of a set screw 39, whose inner end seats within groove 40 formed in the bearing 38. A helical spring 41 is wrapped about the shaft 8, and has one end secured to the arm 36, and its other end secured 55 to the bearing 38. A convenient way of

securing the ends of this spring is to provide apertures for their reception in the lever 36 and the bearing 38.

It will be seen, therefore, that any sliding motion given the sleeve 34 by the centrifugally responsive means will be imparted to the arm or lever 36, and will therefore rock the transverse control shaft 8, thereby varying the position of the pivot point of the lever 10. It will also be seen that the desired tension may be given the spring 41 by adjusting the bearing 38, and that such adjustment may be maintained by locking the bearing in its adjusted position by means of the set screw 39.

It will be seen that a combined governor and fan mechanism have been provided for an internal combustion engine, and so organized that the mechanism may be carried in a dust proof and oil proof housing 75 of pleasing contour. It will also be seen that a single shaft suffices both for the governor and fan, and that the governor is positively driven from the engine while the fan is yieldably driven therefrom.

I claim:

1. In combination, a housing, a shaft mounted therein and having one end projecting outwardly therefrom, a governor bracket rigidly mounted upon said shaft and positioned within said housing, governor mechanism carried by said bracket, control means operatively connected with said mechanism and projecting outwardly through said housing, a fan loosely mounted upon the outwardly projecting end of said shaft, and resilient means operatively connecting said fan and shaft.

2. The combination of an internal combustion engine having a casing, a shaft positively geared to such engine, a fan loosely carried by said shaft, a spring rigidly attached at one end to said shaft and rigidly attached at its other end to said fan, a governor rigidly attached to said shaft, and a casing enclosing said governor and opening into said engine casing to provide a housing for the gearing connecting said engine and governor.

In testimony that I claim the foregoing 105 I have hereunto set my hand at Antigo, in the county of Langlade and State of Wisconsin.

BEVERLY W. KEESE.
